UNITED STATES PATENT OFFICE.

HARRY S. GAIL, OF HIGHLAND PARK, ASSIGNOR TO FREDERICK C. AUSTIN, OF CHICAGO, ILLINOIS.

HOISTING AND DROPPING APPARATUS.

SPECIFICATION forming part of Letters Patent No. 367,903, dated August 9, 1887.

Application filed February 11, 1887. Serial No. 227,263. (No model.)

To all whom it may concern:

Be it known that I, HARRY S. GAIL, a citizen of the United States, residing at Highland Park, Lake county, Illinois, have invented 5 certain new and useful Improvements in Hoisting and Dropping Apparatus, of which the following is a specification.

The object of my invention is to make a hoisting and dropping apparatus that will increase the number of times the tool or weight is raised and dropped with a given power and dispense with the reverse or back motion now employed in machines of this class to permit the tool or weight to drop; and my invention 15 is particularly designed for use in drilling wells, driving piles, and similar work; and it consists in the features and details of construction hereinafter described and claimed.

In the drawings, Figure 1 is a rear elevation 20 of the operative parts by which I hoist and drop the tool. Fig. 2 is a plan view of the same, taken through Fig. 1 just above the shaft which conveys motion to the parts from the source of power, and through the line 2. Fig. 25 3 is a front elevation of the parts shown in Fig. 1. Fig. 4 is a transverse section of the slotted drop and pitman, showing the means of connecting the two together. Fig. 5 is a side elevation of the clutch-lever, taken in line 5 of Fig. 3; and Fig. 6 is a side elevation of the slotted drop, pitman, and other parts, taken 30 in the line 6 of Fig. 3.

In the drawings, A represents the framework on which the operative parts of my improved hoisting and dropping apparatus are located. B is the walking-beam; C, the pitman; D, the shaft leading from the source of power; E, a clutch for throwing the parts out of and into gear; F, a beveled gear on the end 35 of the shaft D; G, a beveled pinion meshing into the teeth of the pinion F and rotating a shaft, H; H, a shaft rotated by the beveled pinion G, rigidly attached to and rotating a slotted drop, I; J, horizontal bars above and 40 below the slotted drop I, held by springs close enough together to rub against the ends of the slotted drop as they rotate and exert a frictional pressure on them proportionate to the strength and compression of the springs to retard the velocity of the revolutions of the slot- 45

ted drop when the power is on but the weight off; K, a headed stud connecting the pitman C and the slotted drop I; L, a rope or cable leading over pulleys to the tool, weight, or object to be raised and dropped; M, weights on the 55 walking-beam, and N the slot in the drop I.

In making my improved apparatus for hoisting and dropping a tool, weight, or other object, I make a frame of the proper size and strength to contain and support the operative 60 parts. Near the upper end of this frame I pivot a beam, which I have termed the "walking-beam," and which is provided with weights at its outer end to raise the other end the instant it ceases to be drawn down by the pitman C in the operation of the machine. From a drum, O, located in any suitable position in the frame, a rope or cable passes over as many intermediate pulleys as may be desired, and is attached at its free end to the tool, weight, or 65 other object to be hoisted and dropped. A ratchet-wheel and crank may be employed in connection with this drum to wind or unwind the rope wound thereon and to hold it at such position as may be desired. This drum 70 in the arrangement of its crank and pulley and ratchet is shown in Fig. 3, and need not be further described. The rope, leaving this drum, passes over a pulley located in the free portion of the walking-beam, so that it will rise 75 and fall with the rising and falling of such free portion. I have represented a number of holes in this walking-beam, so that the pulley may be located at such point in the free portion thereof and along the same as may be desired. 80 The further out on the free portion of the walking-beam the pulley is located of course the greater will be the rise and fall which it will have as the walking-beam is operated, and consequently the rise and fall of the tool or weight 85 connected with the free end of the rope will be regulated accordingly. A pitman, C, is pivoted to this walking-beam at its upper end, and connected at its lower end with a slotted drop, I, so that as such slotted drop is 90 revolved it will communicate its motion to the pitman and through it to the walking-beam. The slotted drop I is made, preferably, of two parts bolted together, with a cavity into which the slot passes, and the lower end of the pit- 95 man 100

man is attached to the slotted drop by means of a headed stud or bolt, whose head rests and moves up and down in the cavity, while its body extends out through the slot. This will be understood by a reference to Fig. 4 of the drawings.

A shaft, D, leads from any convenient source of power—water, horse, or steam—and is supported in suitable bearings in the frame, as shown in Fig. 1. The end of this shaft carries a beveled gear, F, which revolves with it when thrown into engagement by means of the clutch E. As represented in Figs. 1 and 2, the clutch is out of engagement. Another short shaft, H, arranged in suitable bearings in the frame-work, carries a beveled gear, G, whose teeth engage with the teeth of the beveled gear F, so that it rotates as the beveled gears are engaged and rotated, as above explained. The other end of this shaft H is rigidly attached to the slotted drop I, so as to carry it around with its rotation. This slotted drop which is thus revolved is arranged between brakes J J, supported on rods with suitable bearings and provided with springs to produce the amount of friction required. It is made, as above said, preferably by having two parts bolted together, with a slot through one of the parts and with a cavity back of the slot, as shown in Figs. 3 and 4. As above said, the lower end of the pitman is connected to this slotted drop by means of a headed bolt or stud that will permit of easy movement along the slot from one end of the drop to the other.

Of course it will be understood that the pitman is arranged on that side of the slotted drop which contains the slot, so that the body of this headed stud or bolt may extend out through the slot. As the shaft D revolves it will cause the shaft A to rotate through the engagement of the beveled gears F and G. This will cause the slotted drop to revolve and will carry the pitman down with its revolutions. This slotted drop rotates in the direction of the arrow shown in Fig. 3, and when it has carried the pitman down to its lowest point, so that the direction of its slot and the direction of the pitman are coincident, the weight on the end of the walking-beam will cause its free portion to instantly rise, and will carry the lower end of the pitman up along the slot to the upper end of the slotted drop, when the revolving drop will again carry the pitman around with it until it has again brought its lower end to the lowest point, when the weight of the walking-beam will again bring it to the top. A spring or cushion of some kind may be employed to

receive the free end of the walking-beam and to prevent undue and perhaps injurious concussion of the parts. Thus it will be seen that with every revolution of the slotted drop the pitman, and through it the free portion of the walking-beam, will be carried down twice instead of once, as would be the case if the pitman were pivoted to the revolving drop in the usual way. It will be evident from this that the free end of the rod and the tool or weight to which it is attached will be twice raised as the free portion of the walking-beam is twice carried down, and twice allowed to drop freely as the free portion of the walking-beam is raised. In this way I secure two movements of the tool or weight up and down with every revolution of the shaft carrying the slotted drop, and I dispense with all reverse and back motion necessary where the tool or weight is raised by winding the rope or cable on the drum and then permitting it to unwind by reversing the revolving motion of the drum.

I do not mean in the foregoing description to limit myself to the precise arrangement of parts described, as it is evident that various changes and modifications may be employed without departing from the principle of my invention, which consists in the employment of a revoluble slotted drop that permits the pitman to rise and to be carried down a second time during a single revolution of the drop with which it is connected. In many cases the walking-beam may be dispensed with and the rope or cable connected directly to the end of the pitman, which in this case may be made very short and only long enough to connect the rope thereto. By the "pitman" I mean that piece which forms the means of connecting the revolving slotted drop directly or indirectly with the tool or weight to be raised, without reference to its length, size, or form.

What I regard as new, and desire to be seen by Letters Patent, is—

In hoisting and dropping apparatus, the combination of a frame, a slotted revoluble drop, a pitman connected at one end to the slotted drop by a connecting bolt or piece movable along the slot, a walking-beam to which the other end of the pitman is pivotally connected, a weight on the walking-beam to draw the pitman back to its normal position as each revolution of the drop brings its slot in a line coincident with the longitudinal axis of the pitman, and means for rotating the slotted drop, substantially as described.

HARRY S. GAIL.
